MULTIPLEX TELEGRAPH SYSTEM

Louis M. Potts, Evanston, Ill., assignor to Teletype Corporation, Chicago, Ill., a corporation of Delaware

Application January 18, 1941, Serial No. 374,991

20 Claims. (Cl. 178—53.1)

This invention relates to printing telegraph systems and more particularly to systems operated selectively according to the principles of simplex or multiplex telegraphy.

The principal object of this invention is to provide a synchronous multiplex telegraph system in which each channel of the system is brought into proper phase relation by the act of establishing synchronism.

Another object of this invention is to provide a flexible telegraph system capable of either start-stop simplex operation or synchronous multiplex operation and readily convertible from one mode of operation to the other.

Another object of this invention is to provide a telegraph system comprising a main channel and a branch circuit normally conditioned for start-stop simplex operation and a means to condition the system for synchronous multiplex operation by the addition of another branch circuit to the system.

A further object of this invention is to provide means to convert from simplex operation to synchronous multiplex operation and vice versa without interrupting transmission over the branch circuit and main channel normally conditioned for simplex operation.

A still further object of this invention is to provide proper phasing and synchronizing of the telegraph apparatus to establish and maintain synchronous multiplex operation in the system.

This invention features a main channel with which a branch circuit is normally directly connected for simplex operation but with which another branch circuit may be connected through a distributor for synchronous multiplex operation. When conditioned for synchronous multiplex operation, the branch circuits at the sending and receiving terminals of the main channel are connected therewith through regularly operated contacts included in synchronous distributors, which distributors operate in synchronism and in phase with one another. In each transmission branch circuit there is provided a start-stop permutation code transmitter operable at random and signal repeating mechanism capable of generating two identical sets of signals which are out of phase with one another. There is also provided means which under the dual control of the transmitter and a transmission phasing cam included in the multiplex distributor selects and applies to the main channel, impulse by impulse, that set of signals which is in suitable phase relation with the multiplex distributor contacts, inserting a variable delay in the transmission circuit due to the operation of the repeating mechanism.

In the first embodiment of the invention the means to control the delay in the transmission circuit and to properly phase the repetition of transmitted signals to the operation of the distributor contacts which connect the branch cir-

cuits to the main channel comprises a pair of regenerative repeaters each of which inserts a delay of half a signal impulse and a pair of polar relays conditioned by the transmitter and the distributor jointly to include one or both regenerative repeaters in the branch circuit and to insert a delay of either one half impulse or two half impulses.

In the first modification of the invention a cam controlled mechanical means is employed in place of a pair of polar relays to control the delay in transmission by including one or both regenerative repeaters in the branch circuit.

The invention in its second modification features a single mechanical repeater in the transmission branch circuit capable of generating two differently phased signal impulses for each impulse received. One of the generated impulses has a time delay with respect to the other and the repeater and multiplex distributor jointly select and apply over the multiplex channel that signal generated by the repeater, which is in proper phase with the operation of the multiplex distributor contacts.

A further feature of this invention resides in the provision of a circuit, energized at one end of the main channel, to place into operation and at the same time to properly phase the distributors at each terminal of the main channel preparatory to establishing synchronous multiplex operation.

As a still further feature this invention provides a relay circuit energized under the dual control of the distributor mechanism and the transmitted signals in the normal simplex circuit to establish synchronous multiplex operation or to return to simplex operation from synchronous multiplex operation without interfering with transmission over the branch circuit normally connected with the main channel.

This invention further features a carrier telegraph system in which each branch channel is provided with distributing mechanism operable to multiply the number of communication channels available in the carrier system.

More specifically, the invention in one application embodies a plurality of main channels to each of which is normally connected for simplex operation thereover, a branch circuit and to each of which another branch circuit may also be connected to afford synchronous multiplex operation and all the main channels may, in turn, be connected permanently to a carrier conductor to form a carrier telegraph system. Associated with each terminal of each main channel is a mechanical distributor which is disconnected therefrom during simplex operation over the main channel and one branch circuit, but which operates, when the synchronous multiplex operation has been established, to connect each of the two branch circuits in alternation for half a signal impulse

period with the main channel, the connection being through a pair of cam controlled contacts in the distributor which operates at a speed of one revolution per signal impulse period.

In order to avoid interrupting the simplex operation and mutilating a signal combination, a relay circuit operates to establish synchronous multiplex operation only when the distributors are operating in phase with one another and at synchronous speed and in proper phase relation with the transmitter operating at random in the normal simplex circuit.

The transmitter in each branch circuit when the system is connected for multiplex operation operates at random but the branch circuits are regularly connected with the main channel and signal repeating mechanism is provided in each branch circuit to generate signals in a suitable phase relation with the operation of the multiplex distributor contacts. The repeating mechanism is controlled jointly by the phase of the incoming signals and a transmitting phasing cam in the multiplex distributor to phase the output of the repeater mechanism with the operation of the multiplex distributor contacts and to maintain this relation for a complete set of signal combinations.

A more complete understanding of the invention may be had from the following detailed description to be interpreted in the light of the annexed drawings wherein:

Fig. 1 shows an assembly of substations, repeater mechanisms, repeater controlling relays and associated circuits for switching the repeating mechanism into and out of service;

Fig. 2 illustrates two central stations including circuits and distributor mechanisms for completing communication channels from the substations of Fig. 1 to substations also designated in Fig. 2;

Fig. 3 shows a modification of the equipment of Fig. 1, employing mechanical relays for controlling the repeaters;

Fig. 4 shows a further modification of the equipment illustrated in Fig. 1 with a combination repeater mechanism substituted for the plurality of repeaters in Fig. 1;

Fig. 5 shows mechanical details for adjusting the followers associated with the distributor cams;

Fig. 6 shows a modified cam follower adjusting mechanism;

FIRST EMBODIMENT

Figs. 1 and 2 when combined present complete circuits illustrating one embodiment of a system employing this invention. In general, conductors 1 and 2 extend from Fig. 1 to Fig. 2 and form a part of branch circuits A and B respectively. Branch circuit A is termed a "basic" circuit be-

cause it is normally conditioned for simplex operation. Reference to Figs. 1 and 2 will show that conductor 1 is normally connected directly to conductor 3 of main channel C through the contacts 17 at relay 55 completing a simplex communication path from a substation 11 to main channel C. Main channel C is shown as part of a carrier telegraph system including a carrier conductor 57 to which the basic circuit is extended over conductor 3 and, therefore, it is proper to call conductor 3 an extension conductor to which basic circuit A is normally connected.

Branch circuit B is termed an "additive" circuit because it is normally out of the telegraph system but may be added thereto. Conductor 2 of circuit B, for example, is normally interrupted at the outer right hand armature of relay 55 and when relay 55 is energized, in a manner to be hereinafter described, circuit B is added to extension conductor 3 in alternation with basic channel 1 through a distributor 21 and its cam controlled contacts.

Conductors 5 and 6 also extend from Fig. 1 to Fig. 2 and are included in operating circuits of the mechanism associated with the circuits above-mentioned. Signaling conductor 9 also extends from Fig. 1 to Fig. 2 and is utilized to control lamps associated with circuit B.

Substation 11 includes a transmitter 12 which may be tape controlled or a direct keyboard type, a home recorder 13 and a receiving recorder 14. Other substations included in the system are similar. A regenerative repeater is symbolized in Fig. 1 at 15 and may be of the type illustrated and described in United States Patent No. 2,105,173 issued to W. J. Zenner et al. and is characterized by the fact that code signals are repeated therefrom impulse by impulse with a time delay of about one-half of an impulse period with respect to received signals. Although a particular type of regenerative repeater is here disclosed, it is to be understood that the type described is chosen for this embodiment of invention only and that any desired regenerative repeater may be employed. Storage repeater 16 and all other repeaters having the same symbol are the same as repeater 15. Polar and neutral relays, tuned relays, and unidirectional valves may be recognized by their well-known symbols.

At 20 is represented a central office through which substations are connected for inter-communication. A transmitting distributor 21 is located at the central office and is driven from a speed controlled motor 28 through gearing 29. The distributor includes a shaft 22 carrying cams 23, 24, and 27 operative to establish and maintain synchronous operation over main channel C, in a manner to be described hereinafter.

A distant central office is designated 30 and it is equipped with a receiving distributor 31 which comprises a shaft 32 driven by speed controlled motor 38 through gearing 39. Cams 33, 34, 36, and 37 carried by shaft 32 operate in synchronism with cams on distributor shaft 22 during multiplex operation.

Orientation between motor phasing cam 37 and distributor cams 33 and 34 is provided by hub 41 on cam 37, the hub being adjustably fixed to shaft 32 by set screw 42. Rectangles 43 and 44 represent regenerative repeaters identical in construction with repeater 15 and controlled by non-biased, polar relays.

The description and mode of operation of the system illustrated in Figs. 1 and 2 will be set forth first for its normal condition of operation,

that is, simplex operation, and then for an alternative condition, such as synchronous multiplex operation. Accordingly, the normal operation wherein the distributors 21 and 31 are idle and wherein only the basic circuit A is connected for a simplex telegraph operation, is as follows:

Permutation code start-stop signals for basic circuit A are generated by transmitter 12 at substation 11 and are transmitted over line conductor 51 to regenerative repeater 15, whence regenerated impulses flow through conductor 52, armature and lower contacts of polar relay 53, to storage repeater 16, the twice repeated impulses flowing thence through conductor 1, contacts 17 of unoperated relay 55 and extension conductor 3 to the winding of polar line relay 56.

A source of alternating current, 500 cycle alternating current for example, is connected to the upper contacts of polar relay 56 and is adapted to be applied to carrier conductor 57 through the armature of the relay 56. Accordingly, as relay 56 is actuated in response to signal impulses received over extension conductor 3 from transmitter 11, pulses of 500 cycle alternating current are placed on carrier conductor 57 and thus the signal impulses are transmitted over the carrier.

The carrier conductor 57 extends the transmission circuit through hybrid coil 63 into a duplex carrier transmission circuit 61, equipped with echo suppressing networks 62. Through a similar hybrid coil 64 the signals are transmitted from duplex circuit 61 into the carrier conductor 45 to tuned relay 65 which is characterized by the fact that it is responsive only to 500 cycle current impulses. Relay 65 repeats the signal impulses in the form of direct currents to polar relay 66 which repeats like direct current signal impulses through extension conductor 67, conductor 68, outer contacts of unoperated relay 69 and regenerative repeater 43 to line conductor 71 and to receiving recorder 72 of substation 73.

Transmission in the reverse direction between substations 73 and 11 is effected by transmitter 74 of substation 73, duplicates of regenerative repeater 15, storage repeater 16 and transmitter distributor 21 represented by rectangle 76, duplex carrier circuit 61, coils 63 and 64, duplicates of relay 65, distributor 31 and repeater 43 represented by rectangle 81, and line conductor 82 to receiving recorder 14 of substation 11.

Through the circuits outlined above, substations 11 and 73 normally are maintained in communication by means of carrier conductors 45 and 57 and extension conductors 3 and 67. Also, each extension conductor extending the transmission circuit to the carrier channel has associated with it only one transmitter, the association being over a basic circuit, such as basic circuit A, associated with extension conductor 3. In other words, in this normal condition each transmitter which is connected to the carrier channel, is connected therewith over a simplex circuit.

The above described operation is predicated upon the idle position of distributor 21 illustrated in Fig. 2, which conditioned the armatures of relays 53 and 83 against their lower contacts and included both repeaters 15 and 16 in the transmission circuit. When distributor 21 is disconnected from extension conductor 3 with its cams displaced 180 degrees from the illustrated position, the normal, simplex transmission circuit is direct to channel 1 from regenerative repeater 15 because in that position of the distributor 21, the armatures of relays 53 and 83 rest against their upper contacts and break the cir-

cuit to repeater 16 at the armature of relay 53. In addition, there is completed from negative battery over a circuit including the armature and upper contacts of relay 83 and repeater 16, a holding circuit which holds repeater 16 inoperative so long as the armatures of relays 53 and 83 remain against their upper contacts. Except for the omission of the repeater 16, the transmission circuit is identical with that previously described.

10 The normal transmission circuit described above, whether it includes one or both of the regenerator repeaters, interconnects substations 11 and 73 for communication over a simplex circuit. With the communication circuit of the system in this condition, additive circuit B is inoperative since conductor 2 terminates at the outer right hand contacts of relay 55 which are open.

20 The circuits and their mode of operation for the alternate condition of the system disclosed in Figs. 1 and 2 will now be described. In this alternate condition the previously defined additive circuit is included in the communication system along with the basic circuit.

25 To initiate the operation of additive circuit B and thus establish the alternate condition, manual key 111 is closed momentarily to energize relays 112 and 113 over an obvious circuit. Relay 112 closes its holding contact to form an obvious holding circuit for relays 112 and 113. Relay 113 operates and connects power conductors 114 to the motor 28 thus placing the motor 28 in operation to drive the distributor shaft 22.

30 In its unoperated condition the relay 112 through its outer right hand contacts has maintained conductor 121 connected to carrier conductor 57 thus supplying an unbroken 1600-cycle current to the tuned relay 122 to supply current of positive polarity to polar relays 123 and 124 and hold open the energizing circuit of motor-control relay 125 at the lower contacts of relay 123.

35 Upon being energized, through the operation of key 111, relay 112 interrupts the supply of 1600 cycle alternating current at its outer right hand contacts but that supply is maintained to carrier conductor 57 through controlled contacts 126 at cam 21. However, as motor 28 drives shaft 22, cam 27 breaks the supply circuit interrupting the 1600 cycle alternating current and, consequently, 40 releasing tuned relay 122 whose armature then applies negative battery to the circuit of relays 123 and 124. Having thus changed the polarity of polar relays 123 and 124, their armatures are conditioned against their lower contacts and an 45 energizing circuit is thereby completed for slow-to-release relay 125 including the armature and lower contacts of relay 123. Relay 125 draws up its armature completing an obvious circuit which 50 operates relay 127 and connects power conductors 128 to motor 38 and starts the motor to drive shaft 32.

55 As motor 28 increases its speed, cam 27 through its controlled contacts 126 supplies pulses of 1600 cycle alternating current from conductor 65 121 to tuned relay 122 which responsively supplies direct currents of alternating polarity to relays 123 and 124 to cause their armatures to vibrate. That is, when the 1600 cycle current is flowing, relay 122 operates and applies positive potential 60 to the circuit of relays 123 and 124 conditioning their armatures against their upper contacts; but when that 1600 cycle current is interrupted through the rotation of cam 27, armature of relay 122 applies negative battery to the relays 123 and 124 to move their armatures against their

lower contacts. Relay 125 is a slow-to-release relay to hold the power circuit to motor 38 closed through the armature of relay 127 when the armature of relay 123 moves to its upper contacts and thus assure continuous operation of the motor 38.

In addition to controlling the supply of power to motor 38 through relay 127, the circuit of the 1600 cycle alternating current also functions as a synchronizing circuit to control the speed of motor 38. As explained above, the rotation of cam 27 causes the armature of relay 124 to vibrate and these vibrations are employed in conjunction with a pair of cam controlled contacts 131 and 132, controlled by cam 37, to apply a shunt across an armature resistance 133 to govern the motor speed. The speed of motor 38 is decreased when resistance 133 is in the armature circuit and accordingly, in order to regulate the motor speed, it is only necessary to control the length of the period during which resistance 133 is shunted out.

In operation, when motors 28 and 38 are properly synchronized, the vibrations of relay 124 in combination with the actuation of contacts 131 and 132 determine the length of the shunting period for resistance 133 in each position of the armature of relay 124. Should motor 38 tend to increase in speed, cam controlled contacts 131 and 132 would open the shunt circuit earlier, shortening the shunted period of resistance 133 and decreasing the motor speed. On the other hand, if motor 38 should tend to lag, the cam 37 would not open the shunt circuit until a later instant in the cycle, elongating the shunt period and increasing the motor speed. In United States Patent No. 726,750 issued to L. M. Potts on April 28, 1903, there is disclosed and fully explained such a synchronizing system and reference may be had to that patent for a more complete disclosure of the principles of such a system.

In addition to synchronizing motors 28 and 38, relay 124 and contacts 131, 132 controlled by cam 37 assure the proper phasing of the distributors 21 and 31 since there is only one position in which shaft 22 can come into synchronism with shaft 32.

Since in the particular embodiment of the invention under consideration the alternate condition contemplates synchronous multiplex operation, it is necessary to defer the establishment of the alternate condition until distributor motors 28 and 38 are operating synchronously, and for the accomplishment of this result, means is provided, as will presently appear, to establish synchronous multiplex operation under the control of both distributor motors.

There is provided at central station 20 a plurality of relays, such as 54, one of which is associated with each extension conductor and which must be operated to convert the extension conductor from simplex to multiplex operation. The circuit for these relays is closed by slow-to-operate relay 136 when motor 28 has attained a predetermined speed. The energizing circuit for relay 136 includes the inner right hand armature of relay 112, secondary of transformer 137, and rectifier 138. The primary of transformer 137 is in a tuned circuit to which alternating current is supplied through contacts 139 actuated by cam 27. Although there will be an alternating current flowing through transformer 137 as the motor 28 comes up to speed, relay 136 is not operated but only when the current of greater in-

tensity which traverses the tuned circuit when the motor is at synchronous speed and voltage of resonant frequency is applied to the tuned circuit. Since relay 136 is slow to operate, it 5 will not actuate until the motor 28 attains and holds its synchronous speed. When relay 136 operates, the circuit including relay 54 and others (not shown) for the remaining communication channels of the system, is completed, thus operating relay 54 preparatory to connecting basic 10 circuit A and additive circuit B to extension conductor 3 through cam controlled contacts 152 and 157.

In each basic circuit there is provided, as already explained, a start-stop permutation code transmitter, such as transmitter 12, which is operable at random and which may be transmitting at the time key 111 is depressed to convert the system from its normal simplex operation to synchronous multiplex operation and it is possible, if no preventive mechanism is provided, to establish the synchronous multiplex operation during the transmission of a character signal over the normal simplex channel and mutilate a signal impulse. Accordingly, a companion relay 55 is 15 associated with each relay 54 to prevent such signal mutilation and maintain communication over the basic circuit even though the system is converted to multiplex operation. Continuing 20 the description of extension conductor 3, basic circuit A, and additive circuit B for illustrative purposes, the operation of the companion relay 25 55 is as follows:

Relay 55 is a three-winding relay wherein the 30 middle and right-hand windings energize the relay initially and the left-hand winding is a holding winding. The circuits for the energizing 35 windings of relay 55 are: ground, cam controlled contact at 151, polar relays 53 and 83, cam controlled contact at 119, conductor 5, cam controlled contact 153 to either line 129, armature 160 of relay 54, right-hand winding of relay 55 to positive battery, or to line 139, armature 161 of relay 54, center winding of relay 55 to negative 40 battery. The circuits just described for the energizing windings of relay 55 include cam controlled contacts 151 and 119 at repeaters 15 and 16, respectively. Upon the receipt by either repeater of the start impulse of a code signal 45 combination, that repeater is set into operation and through a suitable cam opens its cam controlled contacts and retains them open until the receipt of the stop impulse.

Relay 136 in addition to completing the circuit 50 to relay 54, supplies the ground for the obvious holding circuit of relay 55 when the relay is energized including the left-hand winding, contact and inner left-hand armature of the relay 55. When relay 54 operates in response to the 55 actuation of relay 136 by the distributor 27 rotating at the desired speed, armatures 160 and 161 are attracted rendering transmission phasing cam 24 effective to control the circuits of the energizing windings of relay 55. If at this instant no signal is being transmitted over the basic 60 circuit A in the normal simplex circuit, the circuit to relay 55 will be completed through cam controlled contact 153 and either line 129 or 130. Accordingly, the center or right-hand winding of 65 relay 55 will energize the relay, complete a holding circuit therefor through the left-hand winding and inner left-hand armature, complete an obvious circuit over line 9 and the outer left-hand armature of relay 55 for slow-to-operate signal- 70 ing relay 145, and connect basic circuit A and ad-

ditive circuit B through the right-hand armatures of relay 55 to cam controlled contacts 152 and 157, respectively, thus establishing the synchronous multiplex operation.

If at the time relay 54 draws up there is a signal being transmitted over the basic circuit, the energizing circuit for relay 55 will be interrupted at either cam controlled contact 151 or 119 and this condition will prevail until the entire signal combination has been repeated to extension conductor 3. Shortly after the stop impulse is set up in the repeater for transmission, the circuit to relay 55 will again be completed at the cam controlled contacts 151 and 119 and relay 55 will be energized to establish the multiplex condition as described above. The circuit of relay 55, therefore, controlled jointly by the signaling condition of the basic circuit and the distributor mechanism delays establishing the multiplex operation until the stop impulse or no signal impulse is being transmitted over the basic circuit. This assures continuity of transmission over the basic circuit and permits establishing synchronous multiplex operation without mutilating signals in the process of transmission over the basic circuit.

At central station 30, a plurality of relays 69 similar to relay 54 is provided, one for each extension conductor 67, and this plurality of relays is operative to condition the receiving extension conductors for multiplex telegraphy through the distributor cams. The circuit of relay 69 is under the dual control of relay 141 and tuned transformer 143. At 140 there is represented a tuned transformer and an associated rectifier to control relay 141 in a manner identical to that described in connection with relay 136. The alternating current in this instance is supplied through the armature of relay 123 and its frequency is determined by the speed of motor 28 through cam 27 and its controlled contacts 126 which supply the pulses for relay 122 and consequently relay 123. When motor 28 is at synchronous speed, the frequency of this alternating current is the resonant frequency for the tuned transformer and its current operates relay 141. With relay 141 energized, the circuit for relay 69 is closed but that relay will not be operated until the alternating current generated at contact 142 under the control of cam 26 is at resonant frequency for tuned transformer 143. A rectifier 144 is included in the relay circuit and the operation of the circuit to energize relay 69 is precisely the same as that described for the operation of relay 136 through contact 139. Accordingly, it follows that both motors 28 and 38 must attain a predetermined speed, preferably synchronous speed, as a condition precedent to the energization of relay 69.

The sequence of events in starting the distributors 21 and 31 is as follows: The key 111 is closed momentarily, motor 28 starts, motor 38 starts, motor 28 attains predetermined speed, relay 136 receives current but the slow-to-operate armature of relay 136 does not respond at once, armature of relay 141 operates, motor 38 attains predetermined speed and tuned transformer 143 supplies current to relay 69, relay 69 operates and energizes relay 96 over an obvious circuit but the slow-to-operate armature of relay 96 does not respond at once, armature of relay 136 operates and supplies current to relay 54, relay 54 operates, contacts 160 and 161 are attracted, relay 55 is energized during

the stop signal period or when no signal is being transmitted over basic circuit A, and supplies current through its left-hand armature and conductor 3 to slow-to-operate relay 145, the armature of slow-to-operate relay 96 operates, and the armature of slow-to-operate relay 145 operates. The operation of those relays effects the following conditions to establish multiplex operation:

- 10 Upon the operation of relay 69, the direct connection between conductor 68 and regenerative repeater 43 is broken and a substitute path is formed through left-hand contact controlled by cam 33 and through outer left-hand armature of relay 69 to repeater 43. Receiver 72 at substation 73 is now connected to extension conductor 67 for but a brief interval every unitary signal impulse period since distributor shaft 32 as well as shaft 22 completes one revolution in each unitary signal impulse period. Cam 33 is provided with a short recess so that only a small portion of a signal impulse is transmitted thereby. By properly orienting the cam followers, it is possible to pick out that portion of a signal impulse which is least subject to distortion and transmit that portion to a repeater, and thus prevent transmitting wrong signals therefrom. Cam 33 closes its contacts to receiver 72 for but a short period in every signal impulse period and permits the polar relay of the regenerative repeater at 43 to be conditioned by variable polarity voltage supplied thereto from the armature of polar relay 66 in accordance with the signal impulses being transmitted. The regenerative repeater at 43 will regenerate these shorter impulses into full length impulses for propagation over conductor 71 to receiving recorder 72 at substation 73. The contacts of distributor cam 33 will come into operation in phase with signals generated initially at substation 11, because the contacts of cams 27 and 37 will have phased the distributor shafts 22 and 32.

When slow-to-operate relay 136 operates, it energizes relays 54 and 55 and the connection at 47 between conductor 1 and extension conductor 3 is interrupted and a substitute path is formed from conductor 1 through inner right-hand contacts of operated relay 55 and contacts 152 controlled by cam 23 to extension conductor 3, thus including distributor contacts 152 of cam 23 in the transmission path of basic circuit A. The conductor 1 now occupies but one half of the time of extension conductor 3, the other half time being now available for the additive circuit D through cam controlled contacts 151. Thus the transmitting portion of the system is conditioned for synchronous multiplex telegraphy in which transmission from basic circuit A and additive circuit B over extension conductor 3 is impulse by impulse with succeeding signal impulses originating alternately in circuits A and B.

When slow-to-operate relay 96 operates, its armature connects the transmission line 57 through to receiving recorder 146 at substation 147 by means of tuned relay 68, polar relay 66, line 67, right-hand contacts controlled by cam 33, inner left-hand armature of relay 69, armature of relay 96, and regenerative repeater 44. With additive circuit B connected in this manner with its receiver 146, the synchronous multiplex system is complete. Slow-to-operate relay 145 when operated energizes lamp 134, indicating to the operator at station 148 that conductor 2 is now conditioned for operation. Relays 96, 136 and 145

are constructed or adjusted to such delay periods of operation as is required to assure the closing of their contacts in the desired order.

The operation of the additive circuit between substations 147 and 148 is identical with the described operation of the basic circuit, the additive circuit utilizing regenerative repeater 149, storage repeater 150, alternative contacts in relays 55 and 69 and alternative contacts controlled by cams 23 and 33 respectively and sharing the line time with basic circuit A.

As indicated previously, there is provided a means for changing the polarity of the power applied to relays 53 and 83 in order to vary the positions of their respective armatures. In the present embodiment, a contact 153 is actuated by a transmitting phasing cam 24 to apply potential over line 5 to relays 53 and 83 and there is included in this circuit the cam controlled contacts at regenerative repeaters 15 and 16 so that the circuit is operative only when it is completed at each repeater. Under the influence of cam 24, contact 153 vibrates between co-operating contacts to apply alternately positive potential from line 129 and negative potential from line 130 to the relay circuit. In like manner, there is alternately applied positive and negative potentials respectively from lines 156 and 155 to contact 154, line 6, cam controlled contacts and relay windings of regenerative repeaters 149 and 150 associated with additive circuit B. It may be seen in Fig. 2 that there is included in the circuits to relays 53 and 83, armatures 160 and 161 to render the relay circuit to regenerative repeaters 53 and 83 inoperative until distributor 21 attains predetermined speed.

As explained above, upon the reception of the start impulse at a regenerative repeater, such as 15, the circuit to the polar relays 53 and 83 is interrupted at the cam controlled contacts at the repeater and remains interrupted until the reception of the stop impulse. Therefore, battery applied over line 5 through contact 153 is effective on the relays 53 and 83 only when the regenerative repeaters have finished repeating the signal impulses and received the stop impulse and, accordingly, there can be no mutilation of the signal combination which would result if the polarity of the relays 53 and 83 were changed during transmission of a code signal combination.

The operation of the transmitting phasing cam 24 and its contacts 153, 154 is as follows: A cam in regenerative repeater 15 moves away from its follower and opens its electrical contact 151 upon receipt of the starting impulse of a permutation code signal, retaining the contact 151 open until receipt of the stop impulse of the code signal. With distributor cams 23 and 24 in the angular positions shown, cam contact 152 is closed connecting conductor 1 to relay 56 for transmission and contact 153 is closed to supply negative battery over line 5 to relays 53 and 83, positioning their armatures against their lower contacts and including storage repeater 16 in the transmission circuit. Should a starting impulse begin at this instant at substation 11, it would be delayed one half impulse period by the regenerative repeater 15 and the repeated starting impulse would be emitted from repeater 15 when cam 23 had rotated one half revolution, opened contacts 152 and disconnected conductor 1 from relay 56; accordingly, the starting impulse must be delayed for a further half impulse period until contacts 152 may be reclosed by the cam 23. Since the starting impulse was received with armatures of relays

53 and 83 against their lower contacts, the storage repeater 16 is included within the transmission circuit. Thus, the starting impulse emitted by repeater 15 is transmitted into storage repeater 16 instead of into conductor 1, and at an instant one half impulse period later it is emitted from storage repeater 16 into conductor 1, at which instant the contacts 152 are closed and conductor 1 is connected to relay 56 for transmission of the impulse into the carrier conductor 51.

A starting impulse initiated at substation 11 when contacts 152 are open will be delayed for one half signal impulse period in the repeater 15 and therefore, will be emitted from the repeater 15 when the contacts 152 have been closed. In such instance, cam 24 will be in a reverse position from that shown in the drawings at the reception of the starting impulse and the reverse polarity of current will be applied to the windings of the polar relays 53 and 83 positioning their armatures against their upper contacts. This setting of relays 53 and 83 connects conductor 52 directly to conductor 1 through the upper contact and armature of relay 53, avoiding storage repeater 16. This condition prevails during the reception of the entire signal combination and, accordingly, a delay of one half unitary signal impulse is introduced into the transmission and the repeater 15 emits the regenerated signal impulses when cam 23 has revolved one half revolution and closed contacts 152, completing the transmission circuit from conductor 1 to polar relay 56.

When both the basic and additive circuits are associated over the synchronous multiplex system above outlined and one circuit is idle, such as basic circuit A, the polarity applied to its associated polar relays, 53 and 83, is reversed at every half revolution of the phasing cam 24 vibrating the relay armatures and connecting the main channel and branch circuit to first one and then the other of the repeaters associated with the particular branch circuit. Upon receipt of a starting impulse from substation 11, the cam controlled contact 151 opens the circuit of the windings of relays 53 and 83 and the condition of the relays as determined then is maintained throughout the transmission of the ensuing code signal. The determined condition of relays 53 and 83 inserts a proper delay in the transmission circuit, synchronizing the transmission from the regenerative repeaters with the operation of distributor cam 23. It is understood that each circuit, basic or additive, is equipped with a delay mechanism such as that already described for conductor 1 and each operates in precisely the same manner to maintain proper phase relation between the transmitters and the cam controlled contacts which apportion the line time.

The transmitters in the branch circuits are adjusted to operate at a speed less than the transmission speed of the multiplex. When the branch transmitters are operating at their maximum rate, there will be a gradual shift of phase between the signals generated and the multiplex distributor cams. Accordingly, when multiplex operation has been established and the transmitter in a given branch circuit is operating at its maximum rate, transmission will be through one setting of the regenerative repeaters of that branch for a certain number of complete signal combinations. After the multiplex distributor has crept sufficiently to shift the phase relation of the distributor cams and the signals in that branch circuit, the transmission phasing cam will transfer the branch circuit to the alternate set-

ting of the regenerative repeaters from which transmission will be carried on until the distributor again causes a sufficient phase shift to return transmission to the first setting of the repeater mechanism. The number of signals transmitted from one setting of the repeaters will depend on the speed differential between the branch transmitter and the multiplex distributor. If transmission is from a keyboard, the rate at which the shift takes place will be quite variable. At the beginning of each signal combination, that branch circuit condition is selected which supplies the best phase relation and this condition is maintained for at least the entire signal combination. When the next signal combination is received, whether immediately or some time afterwards, that condition of the branch circuit is selected which affords the best phase relation.

To remove the additive circuit from operation and restore the aforescribed normal condition, manual key 153 is operated momentarily breaking the holding circuit and de-energizing relays 112 and 113. Relay 112 releases immediately and at its outer right-hand contacts completes a circuit to supply uninterrupted 1600 cycle current to carrier conductor 57 to operate tuned relay 122 while at its inner right-hand contacts, relay 112 breaks the circuit to slow-to-operate relay 136. By attracting its armature, relay 122 places and holds the armature of relay 123 against its upper contacts placing a continuous direct current in the circuit of tuned transformer 140 thereby releasing relay 141. At the same time, relay 123 interrupts the circuit to slow-to-release relay 125. With relay 141 de-energized, the circuit for relay 69 is open and the extension circuit 67 is, accordingly, connected directly to receiver 72 since the circuits of the contacts of cam 33 are open at the armatures of relay 69 and receiver 146 is thereby taken out of the circuit.

Relay 136 then releases its armature breaking the circuit of relay 54 causing it to release its armatures and de-energize relay 55. Relay 55 at its outer left-hand armature opens line conductor 9, de-energizes relay 145 and extinguishes line lamp 134 to indicate at substation 148 that its circuit is now inoperative. At its inner right-hand contacts relay 55 connects basic circuit A directly to extension conductor 3 re-establishing the normal simplex circuit and disconnects conductor 1 from contacts 152. Contact 17 is a make-before-break contact, and conductor 1 is connected to extension conductor 3 by contact 11 before being released at the inner right-hand armature of relay 55 thus retaining communication continuously over basic circuit A. At its outer right-hand contacts relay 55 disconnects additive circuit B from extension conductor 3. Relay 54 disconnects at contacts 160 and 161 the transmitting phasing cam 24.

Slow-to-release relays 113 and 125 then operate and stop motors 28 and 38.

The positions of the armatures of the polar relays at the regenerative repeaters at the time contacts 160 and 161 are opened determine whether the storage repeater 16 will be included in the transmission circuit when the system is again conditioned for normal operation. In Fig. 1 storage repeater 16 is included in the transmission circuit.

To keep the circuit drawings clear, there have been illustrated at central station 28 only one pair of branch circuits A and B, and its associated relay circuits, distributor controlled contacts, and transmission phasing cam for properly

allocating the line time of extension conductor C between the branch circuits. At 101, 103 and 105 there are indicated other extension conductors connected to the carrier conductor 57 and as many such extension conductors may be provided as desired. It is to be understood that there will be associated with each such extension conductor a pair of branch circuits, relay circuits, distributor controlled contacts, and a transmission phasing cam in exactly the same manner as described in detail for extension conductor C. In operation each extension conductor of the system will modulate an alternating current of a distinctive frequency in a manner well known in carrier systems.

At central station 30 there are shown a tuned relay 90, actuated by signals received over carrier conductor 45, a polar relay 93, distributor controlled contacts represented at 94, and relay circuits and repeaters indicated at 95 to associate substations 93 and 100 with tuned relay 90. At 102 and 104 are represented additional extension conductors at central station 30 with which similar means is provided to complete communication thereover in a manner contemplated by this invention.

Although a carrier system has been disclosed, the invention is by no means limited thereto and the extension conductors of central offices 28 and 30 may be directly connected, affording a plurality of individual communication circuits each of which would function normally as a simplex circuit and in an alternative condition, function as a synchronous multiplex circuit. To enable such a system to operate under the alternate condition, it is necessary to connect line conductor 21 directly to tuned relay 122 so as to provide a synchronizing channel. With such a circuit arrangement depressing manual key 111 would start motor 28 at central office 28 and motor 38 at central office 30 in synchronism and phase to simultaneously establish multiplex operation over a plurality of distinct circuits and the synchronizing channel would assure the proper phasing of the substation apparatus and the distributor cams in the same manner as that described for the system disclosed in Figs. 1 and 2. Direct current signals may then, of course, be used in place of a modulated carrier current.

Individual channel orientation

Each follower for cam 33 is shown in Fig. 2 as mounted on one arm of a bell crank. All cam followers in the receiving distributor are thus mounted. The details are shown in Fig. 5. Pivoted to the frame of the distributor structure at 159 is a bell crank 162 whose arm 163 carries pivotally the follower 164 of the cams 33 to operate the contacts associated therewith. The arm 165 of the bell crank 162 is pressed by a compression spring 166 which engages a fixed frame member 167 and is urged against an adjustment screw 168 threaded through a member 169 fixed to the frame. As the bell crank member is rotated by its adjustment screw, the cam follower is advanced or retarded with reference to the rotating cam, thus operating its associated contacts earlier or later as desired. There may be provided an adjusting means for each follower of the pair of followers associated with the distributor cams. This feature facilitates adjusting the system and assures synchronous operation.

If desired, a single means may be provided to adjust both cam followers simultaneously. Such an arrangement is illustrated in Fig. 6 wherein

the adjusting means is illustrated in connection with a multi-lobe cam whose utility is to be pointed out subsequently. Of course, this adjusting device may readily be employed with the cam demonstrated in Fig. 5.

In Fig. 6, rocker member 171 is pivoted to the frame at 172 and carries cam follower 173 as well as cam follower 164'. Both cam followers, 164' and 173 pertain to the same extension conductor and are thus adjustable by one rocker member and thumb screw. The members in Fig. 6 which are similar to members in Fig. 5 bear similar numerals primed.

Multiple-lobed cams

The distributors shown in Fig. 2 are illustrated with cams of a single lobe, and shafts 22 and 32 are presumed to rotate at a speed of one revolution per signal impulse line time period. It is possible to increase the number of lobes on each cam and proportionately decrease the rotational speed of the shafts 22 and 32. In Fig. 6 seven lobes 174 are shown on cam 33' corresponding to cam 33, and shaft 32', corresponding to shaft 32, is presumed to rotate at a speed of one revolution per 7-unit code signal time period.

First modification

Figs. 2 and 3 when combined present complete circuits illustrating a modification of the system of Fig. 1 (employing a mechanical means instead of an electrical means for conditioning the delay mechanism). Structural elements in Fig. 3 which have analogous elements in Fig. 1 are provided with numerals having similar tens and units digits and detailed descriptions of such elements are not repeated here.

In Fig. 3, mechanical relays 321 and 322 are provided for operating contacts equivalent to the contacts operated by polar relays in Fig. 1, to place storage repeater 316 either in or out of the transmission line. In the mechanical relay 321, a motor driven shaft 323 acts through friction disc 324 of a friction clutch not otherwise shown to drive two integrally united wheels, namely, ratchet wheel 325 and cam wheel 326, which are restrained either by armature 327 or alternatively by armature 328. A cam follower 331 rests on a lobe of cam 326 and holds contacts 332 and 333 in operated condition (as shown in relay 321) when ratchet 325 is restrained by armature 327, or permits the contacts 332 to assume unoperated contactual relations with respect to contacts 333 when ratchet 325 is restrained alternatively by armature 328 and cam follower 331 rests in a depression of cam 326 (as shown in relay 322).

Magnets 335 and 336 control armatures 327 and 328, respectively, and are energized alternatively by current over conductors 329—129, right-hand winding of relay 55, contact 160 to contacts 153, or conductors 330—130, center winding of relay 55, contact 161 to contacts 153 of cam 24, and conductor 5—305 through cam controlled contacts 319 and 351 to ground.

With the circuits of Fig. 3 coupled to those of Fig. 2 there is illustrated a communication system having both a normal and alternate condition identical to that of the system disclosed in Figs. 1 and 2. Accordingly, the description of Fig. 3 will be limited to the operation of the mechanical relays and it will be assumed that the alternate condition of the system has been established connecting substation 311 over conductor 301 of the basic circuit and substation 348 over

conductor 302 of the additive circuit to extension conductor 3 because, until that condition is established, the mechanical relays are held in one position since the circuits to magnets 335 and 336 are open at contacts 160 and 161.

When shaft 22, Fig. 2, is operating at synchronous speed and neither regenerative repeater 315 nor 316 is repeating a signal combination, contacts 153 of cam 24, will supply current from negative battery, Fig. 3, alternately through magnets 335 and 336. The circuits are: ground, cam contacts 351 and 319, line 305—5, contacts 153 at cam 24 then to either line 129, contacts 160, right-hand winding of relay 55 to line 329, magnet 335 and battery or to line 130, contacts 161, center winding of relay 55, line 330, magnet 336 and battery. When cam 24 is in the angular position illustrated in Fig. 2, magnet 336 is energized, ratchet 325 is restrained by armature 327, follower 331 is resting on a lobe of cam 326, contacts 332 and 333 are closed, and the magnet of storage repeater 316 is energized by current flowing from positive battery, through magnet of storage repeater 316, operated contacts 333 and 332, conductor 352, contacts of regenerative repeater 315, and battery. If the start impulse of a signal combination were received by regenerative repeater 315 at such an instant, the repeater would start and would open the cam controlled contacts 351, breaking the circuits to both magnets 335 and 336, thus retaining the cam 326, follower 331 and contacts 332—333 in the conditions illustrated, and resulting in the operation of storage repeater 316 in response to the operation of regenerative repeater 315. The contacts of storage repeater 316 then would operate to transmit signals over conductor 301—1 to relay 56 and to the carrier conductor 57. In this condition with repeaters 315 and 316 in the transmission circuit, a delay of a full signal impulse period is introduced in the transmission, as was true of the corresponding condition of the apparatus of Fig. 1. Because of the cam controlled contacts at each regenerative repeater, this condition prevails until the transmission of an integral number of complete signal combinations.

When cam 24 is in its alternative angular position, with its controlled contacts 153 in reversed contactual relations, magnet 335 is in energized condition, ratchet 325 is restrained by armature 328, follower 331 is in its lowered position, contacts 332—333 are open, and the magnet of storage repeater 316 is energized by current flowing from positive battery, through the magnet of storage repeater 316 and unoperated contacts 332 to negative battery independently of the contacts of regenerative repeater 315. If the start impulse of a signal combination were received by regenerative repeater 315 at such an instant, the repeater would operate and would open the contacts controlled by cam 351, breaking the circuits to magnets 335 and 336 and thus retaining the follower 331 and contacts 332—333 in unoperated condition and resulting in the operation of regenerative repeater 315 to transmit signals directly over conductor 352 and conductor 301—1 to relay 56 without time delay in storage repeater 316. In other words, the transmission circuit would include regenerative repeater 315 only and a delay of half a unitary signal impulse interval would be introduced in the transmission. The local circuit defined for the magnet of repeater 316 under this condition operates as a holding means, holding the repeater 316 locked in its inoperative condition. Again, this setting of

the repeaters 315 and 316 and condition of the transmission circuit is maintained by the cam controlled contacts 319 and 351 for an integral number of complete signal combinations. Since those contacts are not closed until the reception of the stop impulse, there can be no mutilation of the signal combinations.

Signal impulses delivered to conductor 301-1 by repeater 315 or alternatively by repeater 316 will be in a permissible phase relation to the operation of distributor cam 23 for the reasons set forth above in connection with description of operation of the structure illustrated in Fig. 1.

Mechanical relay 322 is similarly operated under the control of the cam contacts of repeaters 349 and 350, conductor 306-6, contacts 154 of cam 24 and return conductors 155-355, 156-356, to the magnets of the mechanical relay 322, thereby controlling the switching of the storage repeater 350 into and out of the transmission path from substation 348 to conductor 302-2 and to relay 56. At 345 is the line relay operative to illuminate lamp 334 when the alternate condition has been established and transmission may be carried on from substation 348.

Second modification.

In this second modification, the regenerative repeater and the storage repeater, illustrated as separate structures heretofore, are combined into one unitary mechanical structure.

Illustrated in Figs. 4 and 7 to 12, inclusive, is a mechanical regenerative repeater of the form shown and described in United States Patent No. 2,105,173, issued to W. J. Zenner et al., the structure of the Zenner et al. patent being modified for the purposes of the present invention to generate two signal impulses at the repeater in response to each received signal impulse, the two regenerated signal impulses being similar in nature but displaced in time from one another. Accordingly, the disclosure of the noted Zenner et al. patent is made a part of this application and will be referred to further herein.

Referring to Figs. 7 to 12, inclusive, there is shown mounted rigidly on a frame plate 410 a pivot stud 411 upon which there oscillate independently an armature member 412 and first and second repeating members 425 and 435, respectively.

The repeater magnet 413 is provided with an armature 412 of yoke form and pivotally mounted on stud 411 by yoke arms 414 and 415 (see Fig. 9). The armature comprises a plurality of extensions, namely, portion 416 which is attracted directly by the magnet, a first cam follower 417 and a second cam follower 418 passing through an opening 423 (see Fig. 10) in frame plate 410 and these followers are controlled by cams 435 and 436, respectively, for mechanically assisting armature 412, a starter striker 419 on an arm 433 to initiate the operation of the repeating mechanism, a latch lever 420 which is a subextension on cam follower 418 and which determines the delay inserted in the transmission circuit, and a pair of anchor arms 421 and 422 to which springs extend and provide a self centering mechanism for repeater tongue 425 with respect to the armature 412.

The regenerative repeater member 425 also pivotally supported by the stud member 411, engages the stud member by yoke arms 424 positioned between the yoke arms 414 and 415. It is provided with a plurality of operating extensions; namely, a pair of signal repeating electrical contacts

426 to transmit the regenerated signal impulses, a pair of transfer abutments 429 and 430 on a lateral arm 427 passing through an opening 428 in frame plate 410 to control regenerative repeater member 435, a lock edge 431 and a jockey edge 432 to hold repeater member 425 in its various positions (see Figs. 8, 10, and 12).

A storage repeater member 435 also is pivotally supported by the stud member 411, engaging the stud 411 by yoke arms 436 and 437 on alternate sides of plate 410 and connected through the web body of the member 435, passing through an opening in the frame plate 410. In front of the frame 410, the web body of the member 435 carries an integral extension 438 provided with a pair of electrical contacts 439 which engage one or the other pair of two pairs of anvil contact points 440 (see Fig. 7). At the back of the frame plate 410, the member 435 is provided with an arm 441 extending from the yoke arm 437 and having a bifurcated end (see Figs. 8 and 12).

Co-operating with the two repeater members 425 and 435 is a transfer assembly for controlling repeater member 435 to cause it to regenerate and repeat signal impulses and it comprises a transfer lever (see Figs. 7, 8, 9, and 12) 442 pivoted on a fixed post 443 and provided with a cam follower 444 and with an extension arm 445 which carries at its distal end a pivot pin 446. The pivot pin 446 carries a transfer T 447 which upon being moved by the arm 445 under power from cam follower 444 may engage alternatively either the abutment 429 or the abutment 430 on extension arm 427 of repeater member 425 and be rotated upon its supporting pin 446.

The particular abutment with which T 447 engages is determined by the position of repeater member 425. That is, if repeater member 425 is in its lower position repeating a spacing impulse, abutment 429 on extension 427 of member 425 is in alignment with and will be engaged by T 447, whereas, when a marking impulse is being repeated by member 425, that member is in its upper position and T 447 will engage abutment 430 (see Fig. 8). Transfer T 447 carries a transfer pin 448 which at all times is confined within the bifurcation of the arm 441 of storage member 435 and which acts to shift the member 435 oscillating upon its supporting stud 411 in response to the shifting of T 447 about its pivot 446.

A continuously driven power shaft 450 is provided as shown in the Zenner et al. patent referred to above. This shaft carries a first cam sleeve 451 and a second cam sleeve 452 (see Fig. 11). The need for a plurality of cam sleeves will be apparent from the description of the operation of the regenerative apparatus. Friction plates 453 and 454 are fixed to shaft 450 while shouldered friction plates 455 and 456 are slidably carried by shaft 450, the shoulders of the plates being splined together and the assembled plates 455, 456 being splined to the shaft by a screw 458 the tip of which enters a keyway (not shown) in shaft 450. Friction rings 460 are provided between the described friction plates and the described cam sleeves. A single compression spring 461 keeps all friction members under pressure.

Cam sleeve 451 is held latched by latching mechanism provided as shown in the Zenner et al. patent but not reproduced here and is released by armature 416 and starting striker 419. Cam sleeve 452 is held latched by a latch arm 470 when the arm is in engagement with a tooth

on cam 467 (see Figs. 8, 9, and 11). A rocker shaft 468, journaled in the frame plate 410, carries fixed upon it at one end the cam follower 469 which follows the cam 466 on the first cam sleeve 451 in front of the frame plate 410, and carries fixed upon it at the other end the latch arm 470 which engages the cam 467 on the second cam sleeve 452 at the back of the frame plate 410.

A latch lever 479 for repeater 425 has the form of an extension arm on a latch lever member 481 of yoke form extending on either side of plate 410, the two yoke arms of which are pivotally supported at the two ends of a stud member 480 fixed in the frame member 410. An extension arm 476 of lever 481 terminates in a cam follower for the release cam 475 on the first cam sleeve 451 and is operated by the cam 475 to operate the lock lever 479 in the manner illustrated and described in the patent to Zenner et al. A further extension arm 478 at the opposite end of lever 481 terminates in a cam follower for the release cam 477 on the second cam sleeve 452 (see Figs. 7, 9, and 12). A spring 449 urges lever 481 counterclockwise, retaining its follower projections against these cams.

Springs 482 and 483 approximately alike in all dimensions, extend respectively from anchor arms 421 and 422 on the armature member 412 to regenerative repeater member 425, providing a self centering articulation. A jockey 491 pivoted at 498 is retained by spring 499 against the described jockey edge 432 on the repeater member 425 (see Figs. 7 and 9).

Cam sleeve 452 carries a cam 484 for the described cam follower 444 of the transfer assembly 442. Cam sleeve 451 carries a cam 485 for follower 417 and cam sleeve 452 carries a cam 486 for follower 418, both followers 417 and 418 being integral with armature member 412 as described above.

Means is also provided for maintaining the delay inserted in the transmission system at a given value for the duration of the transmission of an integral number of complete signal combinations. Cam sleeve 452 carries a cam 487 (see Figs. 8 and 9) for a cam follower 489 integral with a lever 488 of yoke form pivotally supported upon a fixed stud 490 carried by plate 410 one arm of the yoke passing through an opening 496 (see Fig. 7) in the frame plate 410 and being provided with the said integral cam follower 489 and with a notched locking extension 492. A rocking latch 493 pivoted upon a fixed pivot 494 may engage the notch in the extension 492 as illustrated in Figs. 8 and 12 and may be rocked out of latching position by the operation of the described striker 420 (see Figs. 9 and 12) on armature member 412 upon the receipt of the starting impulse.

Reference to Fig. 13, wherein there is illustrated a timing chart for one particular embodiment of the combined repeater mechanism, will demonstrate the necessity for a plurality of cam sleeves and render the subsequent description of the operation of the apparatus more easily understandable.

In Fig. 13, A represents a start-stop code signal received by magnet 413, the start impulse of which releases first cam sleeve 451;

B represents the operation of cam 466 and shows at b the release of second cam sleeve 452 one half a signal impulse period after the release of first cam sleeve 451;

C represents the actuation of release cam 475 permitting the position of repeater member 425 to correspond to the position already assumed by armature 412 and at c there is indicated the release of repeater member 425 one half an impulse period after the reception of the start impulse, interposing a delay of one half a signal impulse period between the received signal combination and the signal repeated by the first regenerative repeater unit;

D represents the cycle of transfer cam 484 and demonstrates at d the transfer of the first, or start, impulse through the transfer mechanism to the second, or storage, regenerative repeater member 435 at a full impulse period after the received start impulse; that is, when the No. 1 signal impulse reaches the repeater magnet, the start impulse is being transferred to the second regenerative repeater 435;

E illustrates the operation of cam 485 to assist the operation of the armature 412 and e indicates the operation of follower 417 by this cam so that the armature is under the control of the No. 1 received impulse;

F discloses the operation of release cam 477 which is similar to that of release cam 475 in point of time but shows the releasing mechanism to be under the control of a cam on sleeve 452 for all signal impulses except the start impulse;

G is a diagram of the cycle of cam 486 for providing assisted armature operation and the cam is actuated in a manner similar to that of cam E except that cam 486 is for those impulses exclusive of the first impulse;

H and I represent the signals repeated by regenerative repeaters 425 and 435, respectively, and show the delay of one half a signal impulse period in signals transmitted by repeater 425 and a delay of a full signal impulse period in the signals transmitted by repeater 435;

J represents the operation of cam 487 to return the control to magnet 505 when storage repeater 435 is transmitting the stop impulse.

A study and comparison of curves A, B and D will reveal that the transfer of the stop impulse from the transfer mechanism to repeater 435 takes place at d1 at which time the original stop impulse has been fully received by magnet 413 and first cam sleeve 451 is at rest. Hence, if transfer cam 484 were carried by first cam sleeve 451, the stop impulse would not be transferred to repeater 435 and for that reason a second cam sleeve 452 is provided to accommodate the transfer cam 484.

At g5 is indicated one time at which the armature 412 is mechanically translated to its attracted position to afford assisted armature action and it is there clearly illustrated that this is very near the time at which first cam sleeve 451 is arrested, having completed one cycle. Similarly, at f6 there is represented the time at which repeater member 425 is released to be positioned to transmit the stop impulse and this, too, occurs at nearly the time when the first cam sleeve 451 is arrested. Although it is possible to arrange cams 485 and 475 to perform all the armature assisting and releasing operations respectively, the present embodiment of the invention contemplates dividing these operations, as disclosed, between cams 485, 486 and cams 475, 477. Since the second cam sleeve 452 is necessary as above shown, the additional cams 486 and 477 are also mounted thereon to permit more facile orientation and assure the required time relationships. The particular al-

location of operations between cams 485, 486 and cams 475, 477 is not important and, if desired, cam 486 may be a one tooth cam, as may cam 477. The cams 486 and 477 are provided in order to provide for more certain time relationships at the times indicated at 95 and 16, respectively.

In the first two modifications of this invention there was illustrated a cam switch at each regenerative repeater, provided to assure that the delay inserted in the transmission circuit be maintained during the transmission of an integral number of complete signal combinations to prevent signal mutilation. Means is provided in the present modification to give the same assurance and it comprises contacts 501, 502, and 503 controlled by armature 504 of magnet 505 (see Figs. 4, 7, and 12). In the condition shown in Fig. 4, armature 504 has connected communication line 401 to storage repeater 435 introducing a delay of a full signal impulse in the transmission circuit. With armature 504 attracted, line 401 is connected to regenerative repeater 425 with a delay of half a signal impulse in the circuit. The locking edge 491 of member 488 operates under the control of cam 487 to maintain armature 504 in the condition existent upon the receipt of the start impulse for the transmission of one entire signal combination. Curve J demonstrates that the locking edge 491 is not operated to release armature 504 until after the transfer of the stop impulse to repeater 435, at which time first cam sleeve 451 has been arrested and, therefore, second cam sleeve 452 is necessary to provide a release for armature 504 after a signal combination has been fully repeated by repeater 435 as well as repeater 425.

Circuits for connecting the combination repeater into the system are illustrated in Fig. 4, which when joined to Fig. 2 shows complete circuits for the second modification of the invention. Substation 511 and combination repeater 512 are connected over conductors 401 and 405 to lines 1 and 5 of a basic circuit of the system, while substation 513 and combination repeater 514 are connected over conductors 402 and 406 to lines 2 and 6 of the companion additive circuit of the system.

This system, as was true of the previously described modification, has a normal and an alternate condition, the former of which will be described now. Referring to Figs. 2 and 4 in combination, it will be presumed that the mechanical distributors 21 and 31 are not operating and that substation 511 is not transmitting, the entire system being mechanically inert but being in a condition of electrical preparedness. Magnet 413 is held energized by current in a circuit through the transmitter at substation 511. Magnet 505 is de-energized because its circuit including contacts 517, conductor 529, right-hand winding of relay 55, armature 160, line 129, contacts 153 at cam 24, line 5, line 405 and ground is open at armature 160. Magnet 506 is held energized by current in a circuit including conductors 406-6, contacts 154 and conductor 156-556.

Upon generation of a permutation code signal at substation 511, magnet 413 is de-energized at the beginning of the start impulse. Armature 416 (see Fig. 7) is released and striker 419 (see Fig. 9) releases the first cam sleeve 451 as described in the Zenner et al. patent. Release of armature 416 also operates armature member 412 clockwise under the force of spring 434 and striker 420 which engages and rocks the latch 493 to release the locking member 488 which,

urged by the tension of spring 485, engages the armature 504, preventing the shifting of the contact spring 501 during the period of transmission of the then ensuing code signal. Because 5 of the movement of armature member 412, one of the springs 483 now tensions the repeater member 425 against the latch 479.

After a delay of one half signal impulse time period, cam 475 operates the follower 476 and latch 479 as described in the Zenner et al. patent and the cam 466 operates the follower 469 to rock shaft 468 and latch 470 thus releasing the second cam sleeve 452 with a delay of one half signal impulse time period after the release of 15 the first cam sleeve 451. Latch 479 momentarily releases the repeater member 425 which shifts its abutments 429, 430 and also operates its electrical contacts 426 thus repeating the starting signal impulse into the contacts 426 20 with a time delay of one half signal impulse period as compared with the original signal impulse.

After a further delay of approximately one half signal impulse time period from the instant of 25 operation of the contacts 426, and just preceding the beginning of the No. 1 character code impulse of the permutation code signal, presumed to be an impulse of marking signal nature, cam 484 operates its follower 444 which propels the 30 T 447 against the shifted abutment 429 and by the resultant rocking of the T 447 effects a shifting of arm 441 and storage member 435 to repeat the starting signal impulse into the contacts 429 with a time delay of one full signal impulse period 35 as compared with the original signal impulse.

The first impulse is then received, energizing magnet 413 but with the holding type magnet employed, the magnet is not strong enough to attract its armature. After the No. 1 impulse 40 has been sustained for nearly half a signal impulse period, cam 485 operates its follower 417 to restore armature member 412 to its attracted position as described in the Zenner et al. patent, thus causing spring 482 to tension repeater member 425 for a marking signal impulse. Since a 45 marking impulse is being received, magnet 413 now retains armature 412 in its attracted position. The employment of a holding magnet of this nature enables the multiplex to be conditioned 50 by only a part of the received signals and consequently, limited mutilation of the received signals is eliminated and not transferred into the multiplex system.

At an instant one half signal impulse time 55 period after the beginning of the No. 1 impulse in magnet 413, cam 477 operates its follower 478 and latch 479 to momentarily release the repeater member 425 which is then shifted by spring 482 to repeat the marking impulse into contacts 426 and to shift abutments 429 and 430. At an instant approximately one full signal impulse time period after the beginning of the No. 1 impulse in magnet 413, cam 484 operates its follower 444 and propels the transfer T 447 against restored 60 abutment 430 to operate the storage repeater member 435 and to repeat the No. 1 signal impulse into the contacts 439 with a delay of one full signal impulse time period after the beginning of the No. 1 signal impulse in magnet 413. In like manner the remaining impulses of the signal combination are repeated at contacts 428 and 439.

During the time period of the stop impulse of the received code signal the first cam sleeve 451 is stopped by stop arm 474 as described in the

Zenner et al. patent and one half signal impulse period later the second cam sleeve 452 is stopped by engagement of cam tooth 467 with latch arm 470. Just before the second cam sleeve 452 stops, cam 487 engages its follower 489 and shifts the locking member 488 into position to release the armature 504 in which position the locking member 488 is engaged by locking latch 493 and is restrained pending receipt of a starting impulse by the magnet 413. All apparatus is again at rest.

During the receipt and retransmission of each successive code signal, the signal impulses are repeated into contacts 426 with a delay of one half impulse period and also are repeated into contacts 439 with a delay of one full impulse period. The position of contact spring 501 determines whether the basic circuit 401 shall be connected to contacts 426 for retransmission with a delay of one half impulse period or to contacts 439 for retransmission with a delay of one full impulse period. The position of contact spring 501 is determined by the position of armature 504 at the instant that the locking member 488 is unlatched by the armature 416 acting through striker 420 and latch 493 in response to a received starting impulse of a code signal combination.

In the normal condition of the particular embodiment of the invention under consideration, magnet 505 is de-energized, as illustrated in Fig. 4 and accordingly, line 401 is connected to storage repeater 435 and there is a full signal impulse period delay inserted in the circuit.

The alternate condition of the system, wherein the basic and additive circuits are operative, will now be considered and it will be assumed that the system is conditioned for synchronous multiplex telegraphy.

When additive circuits are being used, the distributors 21 and 31 rotate continuously and magnets 505, 506 receive impulses of current in uninterrupted sequence from contacts 153, 154 of cam 24.

The signal impulses for the basic circuit are transmitted through contacts 152 (see Fig. 2). Should the beginning of the start impulse in magnet 413 occur with distributors 21 and 31 operating and with the distributor cam 24 transiently in the position shown with contacts 152 closed, conductor 129 would be open at contact 153 of cam 24, magnet 505 would be de-energized and contact 501 (see Fig. 4) would be in engagement with contact 503, as shown, connecting conductor 401 to contacts 439 of storage regenerative repeater 435. At a half impulse period later, the contact 152 will be found open and the starting impulse will be transmitted into contacts 126 ineffectively. At a further half impulse period later the contact 152 will be found closed and the starting impulse will be transmitted into contacts 139, thence through contacts 503, 501, conductor 401-1, contacts of operated relay 55, contact 152 and extension conductor 3 to line transmitting relay 56. Upon the receipt of the start impulse, locking lever 488 operates and holds armature 504 immobile during the ensuing signal combination.

Should the beginning of the start impulse in magnet 413 occur with distributors 21 and 31 operating and with the distributor cam 23 transiently in its position alternative to that shown, with contacts 152 open, conductor 129 would be closed at contact 153, magnet 505 would be energized and contact 501 would be in engagement with contact 502 connecting line conductor 401 to the regenerative repeater 425. At a half im-

pulse period later, the contact 152 will be found closed and the starting impulse will be transmitted into contacts 426 thence through contacts 502, 501, conductor 401-1, contacts of operated relay 55, contact 152 and extension conductor 3 to line transmitting relay 56. Signal impulses will be repeated into contacts 439 but without effect since they are disconnected from the line.

The operation of combination repeater 514 is identical with operation of repeater 512, transmission being over conductor 402-2 of the additive circuit and contacts 151 of cam 23 to relay 56. The operation of cam 23 in allotting the line time to basic circuit A and additive circuit B is precisely the same as that described above in connection with Figs. 1 and 2.

At the end of each revolution of second cam sleeve 452 the cam 487 engages its follower 489 and operates the locking member 488, withdrawing the locking edge 491 from engagement with armature 504, permitting the armature 504 to respond to magnet 505 according to the energized or unenergized condition of the magnet 505. The contact spring 501 thus may be readjusted invariably by the transmitting phasing cam 24 between successive code signals even though the successive code signals are continuous as would be the condition with a tape controlled transmitter operating at station 511.

Locking lever 488 carries two contact operating devices, shown diagrammatically in Fig. 4, for operating contacts 517 and 518 to prevent signal mutilation by converting to multiplex operation during the transmission of a signal combination over the basic circuit. That is, upon the receipt of a start impulse by magnet 413, latch 493 is rocked and lever 488 rotates counterclockwise under the influence of spring 495 disengaging contacts 517 and 518. Should key 111 be depressed at this time, the establishment of multiplex operation would be delayed because the circuits to the energizing windings of relay 55 are disabled at contacts 517 and 518. Upon the receipt of the stop impulse, member 488 is rotated clockwise by cam 487 and closes contacts 517 and 518 permitting relay 55 to be energized over the circuit including battery, magnet 505, contacts 517, line 529 and right-hand winding of relay 55 or the circuit including battery, contacts 518, line 530 and center winding of relay 55. From relay 55, each circuit is completed through contact 153, line 5-405 and ground. Accordingly, conditioning the system for the multiplex operation may be accomplished without interrupting transmission over the basic circuit.

When the system is conditioned for multiplex operation and one of the branches, say line 401, is idle, the transmitting phasing cam 24 through contact 153, line 129 and 529 alternately energizes and de-energizes magnet 505, vibrating armature 504 and connecting line 401 alternately to repeater contacts 426 and 439 in phase relation with the operation of contacts 152. Consequently, when the multiplex condition is once established, it is maintained and no matter when transmission is resumed on line 401, it will be properly phased with respect to the operation of regularly operated contacts 152.

As a matter of convenience, extension conductor 3 has been referred to in the appended claims as a main channel and it is this channel which is conditioned for either simplex or synchronous multiplex operation. Similarly, conductor 1 has been referred to as a branch channel since it extends the conductor 3 and this con-

ductor 1 operates as a start-stop simplex channel at all times.

Three modifications of the invention have been illustrated. Many modifications conforming to limitations and rearrangements may be constructed without departing from the spirit of the invention and the scope of the appended claims.

What is claimed is:

1. In a multiplex telegraph system, a communication channel, a plurality of permutation code impulse transmitters, a mechanical distributor including a pair of contacts individual to each transmitter and through which all code combinations of impulses from the respective transmitters are transmitted, relay means for associating each transmitter with its pair of contacts, and cam means constituting a part of said distributor for operating said pairs of contacts to connect each transmitter cyclically to said communication channel for multiplex operation and maintain said contacts closed for the period required to transmit a complete code combination of impulses.

2. In a multiplex telegraph system, a telegraph circuit, a transmitter associated with said circuit, a contact operated at regularly recurring intervals to complete and maintain said telegraph circuit for the period of a code signal, a contact controlled by signals from said transmitter and operated at random intervals to generate code signals corresponding to those produced under the control of said transmitter, and means controlled by said code signals to transmit through said contact operated at regularly recurring intervals all of the succession of impulses composing said code signals as determined by said transmitter.

3. In a telegraph system, a main channel, a branch circuit, means connected to said branch circuit to transmit at random intervals signals composed of a plurality of unit impulses, means controlled by said signals to transmit over said main channel uniformly timed signals corresponding to said random signals, and means for maintaining the maximum lag between said random signals and said uniformly timed signals to approximately one unit impulse.

4. In a telegraph system, a main channel, a branch circuit, means in said branch circuit to transmit signals, first means in said branch circuit to repeat said transmitted signals, means to time the transmission of signals from said branch circuit to said main channel, means to connect said first repeater means directly to said main channel when said timing means bears a proper phase relation to said transmitted signals, a second means in said branch circuit to repeat said transmitted signals, means to connect said first repeater means to said second repeater means when said timing means bears an improper phase relation to said transmitted signals, and means to connect said second repeater means to said main channel.

5. In a telegraph circuit, a main channel, a branch circuit extending from said main channel, synchronous telegraph apparatus operable over said main channel, start-stop telegraph apparatus including a transmitter operable over said branch circuit, means operable over said branch circuit to generate a first set of signals corresponding to the signals emitted by said transmitter, means operable over said branch circuit to generate a second set of signals identical with said first set but lagging said first set by a predetermined amount, and means to ap-

ply one or the other of said sets of generated signals to said main channel in accordance with the phase relation of said start-stop apparatus and said synchronous apparatus.

6. In a communication system, a synchronous multiplex channel, a start-stop branch circuit, synchronous telegraph apparatus operable over said synchronous channel, start-stop apparatus including a transmitter and two signal regenerators operable over said branch circuit, means to connect said synchronous channel to one of said signal regenerators in accordance with the phase relationship of said synchronous apparatus and said start-stop apparatus, and means to maintain said connection for an integral number of the complete character signal intervals.

7. In a communication system, a synchronous multiplex channel, a start-stop circuit, synchronous telegraph apparatus operable over said synchronous channel, start-stop apparatus including a transmitter and two signal regenerators operable over said start-stop circuit, and means for invariably connecting said synchronous channel to said generators in alternation when said transmitter is idle to maintain proper phasing between said start-stop apparatus and said synchronous apparatus.

8. In a telegraph system, a synchronous multiplex channel, synchronous telegraphic apparatus operable over said multiplex channel, a start-stop circuit, start-stop apparatus including a transmitter and two repeaters connected in tandem operable over said start-stop circuit, and means controlled jointly by signals emitted by said transmitter and said synchronous apparatus to selectively connect one of said repeaters to said multiplex channel.

9. In a carrier telegraph system, a plurality of communication lanes, each lane including a main channel, a plurality of branch circuits, and a mechanical distributor comprising a set of contacts for each branch circuit to connect said branch circuits periodically to said main channel, variable transmission delay means in each branch circuit, and means to determine the transmission delay to phase transmission in any branch circuit with its set of contacts in said distributor.

10. In a telegraph system, a transmitting station, a receiving station, a communication line connecting said stations, means including mechanical distributors at both of said stations for increasing the number of communication channels over said line when said distributors are operating, means for operating said distributors, and means for attaining and maintaining synchronism and phase between said distributors, said last named means being responsive to control currents transmitted over said communication line.

11. In a telegraph system, a line conductor, a pair of start-stop permutation code transmitters operating at random, a distributor having distributing contacts connected between said line and both of said transmitters, said contacts operating to connect said transmitters to said line in alternation impulse by impulse thereby creating two transmission channels, further contacts in said distributor, and rotary phasing means normally rotating while transmission is suspended, said phasing means being operative to stop for an integral number of code signal periods under the joint control of said further contacts and the start impulse of a start-stop permutation code signal generated by one of said transmitters to

phase said one of transmitters with the operation of said distributing contacts.

12. In a telegraph system, a main channel, a branch circuit, synchronous telegraph apparatus operable over said main channel including means to connect said branch circuit to said main channel periodically, a start-stop permutation code transmitter operable at random in said branch circuit, means operable over said branch circuit to generate a first set of signals corresponding to the signals emitted by said transmitter, means operable over said branch circuit to generate a second set of signals corresponding to the signals emitted by said transmitter but in delayed time relation to said first set of signals, means responsive to the operation of said transmitter to apply one or the other of said set of generated signals to said main channel in accordance with the phase relation of said transmitter and said synchronous operation, and means to maintain the application of said set of generated signals to said main channel for an integral number of start-stop code signals.

13. In a multiplex telegraph system, a main channel, a branch circuit, a distributor mechanism connected between said main channel and said branch circuit to connect said channel and said circuit periodically for multiplex operation, a start-stop permutation code transmitter operating at random in said branch circuit, a repeater in said circuit comprising a receiving magnet to which said transmitter is connected and two sets of output contacts through either of which said branch circuit may be extended to said main channel, means in said repeater to generate signals at one set of said output contacts corresponding to signals emitted by said transmitter, means in said repeater to generate signals at the other set of said output contacts identical with but in delayed time relation to said first mentioned generated signals, and means controlled dually by said distributor mechanism and said transmitter to extend said branch circuit to said main channel through one of said sets of output contacts in accordance with the phase relation of said transmitter and said distributor mechanism.

14. In a synchronous multiplex telegraph system, a first station, a second station, a telegraph circuit connecting said stations, motor driven control apparatus at said first station, means at said first station for conditioning said control apparatus for signal transmission over said circuit when said control apparatus attains a predetermined speed, control apparatus also at said second station, means at said second station operable upon the establishment of said predetermined speed for placing said control apparatus thereat into operation, and means at said second station for conditioning said control apparatus for signal reception from said circuit upon its attainment of a speed of operation corresponding to the predetermined speed of the control apparatus at said first station.

15. In a synchronous multiplex telegraph system, a first station, a second station, a telegraph circuit connecting said stations, motor driven control apparatus at said first station, means at said first station for conditioning said control apparatus for signal transmission over said circuit when said control apparatus attains a predetermined speed, control apparatus also at said second station, means at said second station operable upon the establishment of said predetermined

speed for placing said control apparatus thereat into operation, means at said second station for conditioning said control apparatus for signal reception from said circuit upon its attainment of a speed of operation corresponding to the predetermined speed of the control apparatus at said first station, and means at each of said respective stations for maintaining said control apparatus at the predetermined speed during signal transmission.

16. In a synchronous multiplex telegraph system, a first station, a second station, a telegraph circuit connecting said stations, motor driven control apparatus at said first station, means at said first station for conditioning said control apparatus for signal transmission over said circuit when said control apparatus attains a predetermined speed, control apparatus also at said second station, means at said second station operable upon the establishment of said predetermined speed for placing said control apparatus thereat into operation, means at said second station for conditioning said control apparatus for signal reception from said circuit upon its attainment of a speed of operation corresponding to the predetermined speed of the control apparatus at said first station, and an indicating means at said first station operative when the control apparatus thereat is effective for communication for indicating such a condition.

17. In a synchronous multiplex telegraph system, a first station, a second station, a line connecting said stations, motor driven control apparatus at said first station, means at said first station for conditioning said control apparatus for signal transmission over said line, and means operated when said control apparatus has attained predetermined speed for operating said first recited means whereby signal transmission may be effected over said line.

18. In a synchronous multiplex telegraph system, a first station, a second station, a line connecting said stations, motor driven control apparatus at said first station, means at said first station for rendering said control apparatus effective for communication over said line to said second station upon the establishment of a predetermined speed of said control apparatus, and means at said first station for indicating the establishment of such a condition.

19. In a multiplex telegraph system, a communication line, a plurality of separate and distinct transmitters for generating equal length code signal impulses, a mechanical distributor including a pair of contacts individual to each transmitter, means for connecting each transmitter with its pair of contacts, and cam means for operating said pairs of contacts at regular intervals to connect each transmitter periodically to said communication line and maintaining such connection for the period required to transmit the impulses for a single code group from the then connected transmitter.

20. In a telegraph system, two stations, a circuit connecting said stations, telegraph apparatus at each of said stations, a motor at each of said stations for driving each of said apparatuses, means at one of said stations for placing both of said motors into operation, and means at each of said stations for conditioning said apparatus at each station for communication over said circuit upon the attainment of a predetermined phase relationship between said motors.

LOUIS M. POTTS.
